DESIGN FOR A COMBINED ARTICLE CONTAINER AND DISPLAY CABINET

Thomas J. Pilliod, Swanton, Ohio, assignor to
The Pilliod Cabinet Company, Swanton, Ohio,
a corporation of Ohio

Application September 20, 1937, Serial No. 71,695

Term of patent 7 years

To all whom it may concern:

Be it known that I, Thomas J. Pilliod, a citizen of the United States, and resident of Swanton, in the county of Fulton and State of Ohio, have invented a new, original, and ornamental Design for a Combined Article Container and Display Cabinet, of which the following is a specification, reference being had to the accompanying drawing, forming a part thereof.

Fig. 1 is a perspective view of a combined article container and display cabinet showing my new design, and Fig. 2 is an end view thereof.

I claim:

The ornamental design for a combined article container and display cabinet, substantially as shown.

THOMAS J. PILLIOD.
